C. E. SCHODER ET AL.

DISPLAY CARTON

Filed Sept. 22, 1921

Inventors,
Charles E. Schoder and
Max A. Troeger;

By Wilbur M. Stone
their Attorney.

UNITED STATES PATENT OFFICE.

CHARLES E. SCHODER AND MAX A. TROEGER, OF NEW YORK, N. Y., ASSIGNEES TO AMERICAN LITHOGRAPHIC COMPANY, OF NEW YORK, N. Y., A CORPORATION OF NEW YORK.

DISPLAY CARTON.

Application filed September 22, 1921. Serial No. 502,329.

To all whom it may concern:

Be it known that we, CHARLES E. SCHODER, a citizen of the United States, and a resident of New York, borough of Bronx, 5 in the county of Bronx and State of New York, and MAX A. TROEGER, a citizen of the United States, and a resident of New York, borough of Manhattan, in the county of New York and State of New York, have 10 jointly invented certain new and useful Improvements in Display Cartons, of which the following is a specification.

This invention relates to display cartons and has for its object to provide an article 15 of the class specified, simple in construction, efficient as a packing case and pleasing in appearance when erected in display position.

With these ends in view our improved 20 article comprises features illustrated in their preferred embodiment in the drawing accompanying this specification, wherein:—

Figure 1 is a perspective view of a carton embodying our improvements, the cover 25 of the carton being opened up from the body thereof. Fig. 2 is a similar perspective view, with the cover projecting below one end of the body, and said cover and body locked in display position. Fig. 3 is a 30 lengthwise mid-section of the carton in erected position. Fig. 4 is a fragmentary perspective view similar to a portion of Fig. 1, showing a modified form of a portion of our improvements. Fig. 5 is a fragmentary 35 perspective view similar to that of Fig. 4, showing a further modification of a portion of our improvements. All the figures of the drawing are to one scale.

Said carton is preferably folded from a 40 unitary blank, and the forward corners 2, 3 of the body 4 and the similar corners 5, 6 of cover 7 may be joined in some convenient known manner, not shown. The rear ends of body sides 8, 9, are provided with 45 inreaching ears 10, 11 preferably of equal width with said sides, respectively, and of a length equal to the height of the cover, thus using all the stock of the edge portions of the blank from the rear edge of the body to the forward (or lower) edge of the cover. 50 These ears are efficient, when positioned as shown in Fig. 1, for assisting in retaining within the body any merchandise packed in said body, and, when positioned as shown in 55 Figs. 2 and 3, are efficient for holding the

cover in display position relatively to said body. To this latter end said ears are provided with transverse angularly disposed score-lines 12, 13, respectively, thereacross for purposes described later herein. Also 60 body sides 8, 9 are severed from bottom 4 by slots 16, 17, at those ends thereof adjacent ears 10, 11, respectively, a distance equal to about two-thirds the width of either cover side 14, or 15. Rear wall 18 of cover 65 7 is hingedly connected to the rear edge 19 of the bottom of body 4 and to the top of cover 7, and that cover rear wall is unattached at its ends from the ends 14^a, 15^a of side walls 14, 15 of the cover, so that said 70 wall 18 may be folded along both its long edges relatively to the body bottom and cover top.

Cover side-walls 14, 15 are provided with 75 slots 20, 21 therethrough, respectively, located preferably close to and parallel with the cover top and beginning at a distance from rear wall 18 slightly greater than the width of one of the cover sides, as 14. Also near the lower (or front) edge of each cover 80 side, as 14, and opposite the slots, as 20, small tabs, as 22, are formed for purposes described later herein.

In erecting our improved carton in display position, ears 10, 11 of the body sides 85 are opened out, cover wall 18 is folded into the cover and cover side-walls 14, 15 are pushed forwardly between ears 10, 11 and into slots 16, 17, respectively, of body 4, whereby ends 14^a, 15^a of the cover side-walls 90 are thrust downwardly below the rear end of said body, thus providing a foot for the elevation of that rear end of the body 4. Then those portions of ears 10, 11 extending 95 beyond creases 12, 13 therein, are inserted in slots 20, 21 of the cover, respectively, thus locking cover 7 in erect position. For added security of ears 10, 11 in slots 20, 21, tabs 22 may be sprung outwardly to 100 overlap the upper edges of said ears, respectively.

In the modification of Fig. 4, the slots as 21^a, corresponding with the slots 20, 21 of Fig. 1, are shifted to about midway widthwise side-walls 14, 15, respectively, and inclined to the long edges of said side-walls. 105 For engagement therewith, ears 10, 11 of Fig. 1 may be shortened as at 11^a Fig. 4 and inserted in slot 21^a up to cover fold 9^a.

In the modification of Fig. 5, to obviate 110

the need of slots 16, 17, ears, as 10, may be assembled inside the cover side-walls, as 14, the end of said ear 10 being pushed outwardly through cover slot 20 and folded 5 against the outer face of cover 7.

We claim:

1. A display carton including in combination a body comprising a bottom, a front-wall and opposite side-walls, a cover adapted 10 for closing over said body, said cover having side walls and an end wall hingedly connected to said body bottom, said cover end wall being severed from the adjacent ends of the cover side-walls respectively, whereby said 15 cover end-wall may be folded into said cover when the carton is erected, thereby providing a downwardly reaching foot for elevating the adjacent end of the body, said body side-walls having ears inreaching from their 20 rear ends respectively, and each of said cover side-walls having a slot therethrough for the reception of the adjacent body-side ear.

2. A display carton including in combination a body comprising a bottom, a front-wall and opposite side-walls, a cover adapted 25 for closing over said body, said cover having side-walls and an end-wall hingedly connected to said body bottom, said cover end- 30 wall being severed from the adjacent ends of the cover side-walls respectively, whereby said cover end-wall may be folded into said cover when the carton is erected, thereby providing a downwardly reaching foot for elevating 35 the adjacent end of the body, said body side-walls having ears inreaching from their rear ends respectively, said ears having transverse angularly disposed folding lines thereacross, and each of said cover side-walls 40 having a slot therethrough for the reception of the adjacent body-side ear.

3. A display carton including in combination a body comprising a bottom, a front-wall and opposite side-walls, a cover adapted 45 for closing over said body, said cover having side-walls and an end-wall hingedly connected to said body bottom, said cover end-wall being severed from the adjacent ends of the cover side-walls respectively, whereby said 50 cover end-wall may be folded into said cover when the carton is erected, thereby providing a downwardly reaching foot for elevating the adjacent end of the body, said body side-walls having ears inreaching from their rear ends respectively, each of said cover side-walls having a slot therethrough for the 55 reception of the adjacent body-side ear and a tab for locking over the respective body side-wall when the carton is erected.

4. A display carton including in combination a body comprising a bottom, a front-wall and opposite side-walls, a cover adapted 60 for closing over said body, said cover having

side-walls, and an end-wall hingedly connected to said body bottom, said cover end-wall being severed from the adjacent ends of the cover side-walls respectively, whereby said cover end-wall may be folded into said cover when the carton is erected, thereby 65 providing a downwardly reaching foot for elevating the adjacent end of the body, said body side-walls having ears inreaching from their rear ends respectively, said body side-walls being severed from said bottom for a short distance adjacent said ears for the admission 70 of the cover side-walls respectively when the carton is erected, and each of said cover side-walls having a slot therethrough for the reception of the adjacent body-side ear. 75

5. A display carton including in combination a body comprising a bottom, a front-wall and opposite side-walls, a cover adapted 80 for closing over said body, said cover having side-walls, and an end-wall hingedly connected to said body bottom, said cover end-wall being severed from the adjacent ends of the cover side-walls respectively, whereby said cover end-wall may be folded into said cover when the carton is erected, thereby 85 providing a downwardly reaching foot for elevating the adjacent end of the body, said body side-walls having ears inreaching from their rear ends respectively, said body side-walls being severed from said bottom for a short distance adjacent said ears for the admission 90 of the cover side-walls respectively when the carton is erected, each of said cover side-walls having a slot therethrough for the reception of the adjacent body-side ear and a tab for locking over the respective body side-wall when the carton is erected. 95

6. A display carton including in combination a body comprising a bottom, a front-wall and opposite side-walls, a cover adapted 100 for closing over said body, said cover having side-walls, and an end-wall hingedly connected to said body bottom, said cover end-wall being severed from the adjacent ends of the cover side-walls respectively, whereby said cover end-wall may be folded into said cover when erected, thereby providing a downwardly reaching foot for elevating the adjacent end of the body, said body side-walls having ears inreaching from their rear ends respectively, said body side-walls being 105 severed from said bottom for a short distance adjacent said ears for the admission of the cover side-walls respectively when the carton is erected, and means for locking the cover in erected relation to said body. 110

In witness whereof, we hereby affix our signatures this 19th day of September, 1921.

CHARLES E. SCHODER.
MAX A. TROEGER.
